GOLF CLUB SHAFT

TECHNICAL FIELD

The present invention relates to a golf club shaft.

BACKGROUND ART

For golfers, flight distance of a ball is one of the important factors when selecting a golf club. Therefore, hitherto, in order to extend the flight distance of the ball, various improvements have been made with regard to shapes and materials of elements forming a golf club.

However, in recent years, in order to suppress an excessive flight distance so as to increase fairness of game, a repulsion performance of a face, club length, and inertia moment of a head are regulated by rules. Thus, improvement of the flight distance is getting more difficult.

Under such a situation, in consideration with the fact that initial velocity of the ball largely influences the flight distance, it is proposed to extend the club length close to an upper limit regulated by the rules so as to increase head speed of the club (for example, refer to Patent Literature 1).

SUMMARY OF INVENTION

Technical Problem

However, by a method of increasing the head speed of the club by extending the club length, a control property of the head is lowered by an extended amount of the club, so that the ball is not easily stricken by a sweet spot of the head. Therefore, a hitting ratio of the ball is deteriorated, the ball initial velocity cannot be stably increased, and as a result, the flight distance of the ball cannot be improved.

In order to solve this, there are needs for suppressing the club length so as to increase the hitting ratio and increasing head weight so as to increase the initial velocity of the ball. However, when the head weight is simply increased, the inertia moment of the club is then increased, and there is a problem that swingability of the club is lowered.

Thus, in order to prevent an increase in the inertia moment of the club without further increasing the club weight, it is thought that a gravity center point of a shaft is moved to the butt side (gripping side).

Movement of the gravity center point of the shaft to the butt side can be achieved by increasing thickness of a butt side part of the shaft in general. However, by this method, a bending rigidity value EI ($\text{kgf}\cdot\text{m}^2$) of the butt side part of the shaft is also increased, so that feeling at the time of hitting the ball and directivity of the hit ball are lowered.

The present invention is achieved in consideration with such a situation, and an object thereof is to provide a golf club shaft capable of improving feeling at the time of hitting a ball and directivity of the hit ball while extending a flight distance of the ball.

Solution to Problem

(1) A golf club shaft of the present invention is characterized in that when a distance from a shaft front end to a shaft

2

gravity center point is L_G and a full length of the shaft is L_S , $0.54 \leq L_G/L_S \leq 0.65$ is satisfied, a shaft weight is 56 g or more, and a bending rigidity value EI at a point of 630 mm from the shaft front end to the shaft rear end side is $3.6 \text{ kgf}\cdot\text{m}^2$ or less.

5 In the golf club shaft of the present invention, when the distance from the shaft front end to the shaft gravity center point is L_G and the full length of the shaft is L_S , $0.54 \leq L_G/L_S \leq 0.65$ is satisfied and a gravity center of the shaft is on the gripping side. Thus, when weight of a head is increased in order to increase initial velocity of a ball, an increase in inertia moment of the club can be suppressed. As a result, swingability of the club is increased and a hitting ratio can be improved, so that a flight distance of the ball can be improved. The bending rigidity value EI at the point of 630 mm from the shaft front end to the shaft rear end side serving as a part where flex of the club at the time of swing is felt is suppressed to be $3.6 \text{ kgf}\cdot\text{m}^2$ or less. Thus, head speed can be improved by utilizing the flex. Since the swingability of the club is increased, the head speed can be further improved.

10 (2) In the golf club shaft of (1) described above, a low elasticity material including fibers with a fiber elastic modulus of 20 t/mm^2 or less may be used for a butt side part. It should be noted that the “butt side part” in the present description indicates a part of 300 mm from a grip end of the club toward the head side.

15 (3) In the golf club shaft of (2) described above, a fiber orientation angle of at least a part of the fibers in the low elasticity material may be 0 ± 10 degrees.

20 (4) In the golf club shaft of (2) described above, a fiber orientation angle of at least a part of the fibers in the low elasticity material may be 45 ± 10 degrees.

25 (5) In the golf club shaft of (2) to (4) described above, the low elasticity material may include 15 to 50 mass % of prepreg containing fibers with a fiber elastic modulus of 20 t/mm^2 or less. It should be noted that “15 to 50 mass %” in this case indicates a ratio of weight of the fibers with the fiber elastic modulus of 20 t/mm^2 or less contained in the butt side part with respect to weight of the fibers contained in the butt side part.

Advantageous Effects of Invention

According to the golf club shaft of the present invention, 45 feeling at the time of hitting the ball and directivity of the hit ball can be improved while extending the flight distance of the ball.

BRIEF DESCRIPTION OF DRAWINGS

FIG. 1 is an illustrative view of a golf club including one embodiment of a golf club shaft of the present invention;

FIG. 2 is an expansion plan of a prepreg sheet included in a shaft in the golf club shown in FIG. 1;

55 FIG. 3 is a plan view of a first merged sheet in the shaft shown in FIG. 2;

FIG. 4 is a plan view of a second merged sheet in the shaft shown in FIG. 2;

60 FIG. 5 is a view for illustrating a measuring method of T point strength;

FIG. 6 is an expansion plan of a prepreg sheet included in a modified example of the golf club shaft of the present invention;

65 FIG. 7 is a plan view of a first merged sheet in the shaft shown in FIG. 6; and

FIG. 8 is a plan view of a second merged sheet in the shaft shown in FIG. 6.

DESCRIPTION OF EMBODIMENTS

In the following, embodiments of the golf club of the present invention will be described in detail with reference to the accompanying drawings.

FIG. 1 is an illustrative diagram showing the entirety of a golf club 1 according to one embodiment of the present invention. The golf club 1 of the present embodiment includes a wood-type golf club head 2 having a predetermined loft angle, a shaft 3, and a grip 4. The head 2 includes a hosel 6 having a shaft hole 5 to which a tip end 3a located at the front end side of the shaft 3 is inserted and fixed. A butt end 3b at the back end side of the shaft 3 is inserted and fixed in a grip hole 7 of the grip 4. The tip end 3a is located inside the head 2, and the butt end 3b is located inside the grip 4. It should be noted that, in FIG. 1, a reference character of "G" indicates the center of gravity of the shaft 3. The center of gravity G is located on a shaft axis inside the shaft 3.

In the present invention, although the weight of the golf club 1 is not particularly limited, it is set in a range from 265 to 290 g. If the weight of the golf club 1 is too light, the strengths of respective elements (parts) forming the golf club 1 become low, and durability of the golf club 1 may deteriorate. Therefore, the weight of the golf club 1 is preferably not smaller than 270 g, and further preferably not smaller than 273 g. On the other hand, if the weight of the golf club 1 is too heavy, it becomes difficult to perform a swing, so that it becomes difficult to increase the head speed. Therefore, the weight of the golf club 1 is preferably not larger than 325 g, and further preferably not larger than 320 g.

Further, although the length of the golf club 1 itself is not particularly limited in the present invention, it is ordinarily from 44.0 to 47.0 inches. If the length of the golf club 1 is too short, a turning radius of the swing becomes small, so that it becomes difficult to obtain a sufficient head speed. As a result, the ball speed cannot be increased, and the flight distance of the ball cannot be extended. Therefore, the length of the golf club 1 is preferably not smaller than 44.5 inches, and further preferably not smaller than 45.0 inches. On the other hand, if the length of the golf club 1 is too long, the swingability of the golf club is decreased, so that the head speed is lowered. Therefore, the ball speed cannot be increased, and the flight distance of the ball cannot be extended. Thus, the length of the golf club 1 is preferably not larger than 46.5 inches, and further preferably not larger than 46.0 inches.

It should be noted that, in the present specification, "club length" is a length measured based on the description in "Appendix II—Design of Clubs" "1. Clubs" "1c. Length" in the Rules of Golf determined by R&A (The Royal and Ancient Golf Club of Saint Andrews).

[Head Configuration]

The head 2 in the present embodiment is a hollow head and has a large inertia moment. For a club having the head 2 with a large inertia moment, the head 2 is preferably hollow since the advantageous effect of improving flight distance can be stably obtained.

There is no particular limitation in the material of the head 2 in the present invention, and, for example, titanium, titanium alloys, CFRPs (carbon fiber reinforced plastics), stainless steel, maraging steel, soft iron, and the like can be used. Furthermore, instead of manufacturing the head 2 using a single material, the head 2 may be manufactured by combining multiple materials as appropriate. For example, a CFRP and a titanium alloy can be combined together. From a standpoint of lowering the center of gravity of the head 2, it is possible to employ a head in which at least a portion of a crown is made from a CFRP, and at least a portion of a sole is

made from a titanium alloy. In addition, from a standpoint of strength, the entirety of a face is preferably made from a titanium alloy.

In the present invention, although the weight of the head 2 itself is not particularly limited, it is preferably within a range from 180 to 210 g. If the head 2 is too light, the kinetic energy of the head 2 cannot be sufficiently provided to the ball, and it becomes difficult to increase the ball speed. Therefore, the weight of the head 2 is further preferably not smaller than 188 g, and particularly preferably not smaller than 192 g. On the other hand, if the weight of the head 2 is too heavy, the golf club 1 becomes heavy and difficult to swing. Therefore, the weight of the head 2 is further preferably not larger than 208 g, and particularly preferably not larger than 206 g.

Furthermore, in the golf club 1 of the present embodiment, the ratio (head weight/club weight) of the head weight to the club weight is set to be not lower than 0.67 but not higher than 0.72. If this ratio is too small, the kinetic energy of the head 2 becomes small and obtaining a sufficient ball speed becomes difficult. Therefore, the ratio is preferably not lower than 0.675, and further preferably not lower than 0.68. On the other hand, if the ratio is too large, the head 2 becomes too heavy and swinging the club becomes difficult. Therefore, the ratio is preferably not higher than 0.718, and further preferably not higher than 0.715.

[Grip Configuration]

In the present invention, there is no particular limitation in the material and structure of the grip 4, and those commonly used can be adopted as appropriate. For example, there can be used one that is obtained by blending and kneading natural rubber, oil, carbon black, sulfur, and zinc oxide, and molding and vulcanizing the materials into a predetermined shape.

In the present invention, although the weight itself of the grip 4 is not particularly limited, it can be set to be not smaller than 27 g but not larger than 45 g. If the weight of the grip 4 is too small, the strength of the grip 4 becomes low, and its durability may deteriorate. Therefore, the weight of the grip 4 is preferably not smaller than 30 g, and further preferably not smaller than 33 g. On the other hand, if the weight of the grip 4 is too large, the golf club 1 becomes heavy and difficult to swing. Therefore, the weight of the grip 4 is preferably not larger than 41 g, and further preferably not larger than 38 g.

[Shaft Configuration]

The shaft 3 in the present embodiment is a carbon shaft, and is manufactured through an ordinarily sheet winding process using a prepreg sheet as a material. In more detail, the shaft 3 is a tubular body formed from a laminated body of a fiber reinforced resin layer, and has a hollow structure. The full length of the shaft 3 is represented as L_s , and the distance from the tip end (front end) 3a of the shaft 3 to the center of gravity G of the shaft 3 is represented as L_G .

The present invention mainly targets a powerful golfer. Therefore, weight of the shaft 3 is set to be 56 g or more by converting into a 46-inches shaft. When the weight of the shaft 3 is less than 56 g, the shaft is too light for the powerful golfer and timing of impact is not easily obtained, so that a hook or a slice is easily produced. As a result, there is a high possibility that the flight distance is not extended. When the weight is less than 56 g, the shaft is too light, so that evaluation of feel at the time of hitting the ball is unfavorable. Therefore, the weight is preferably 57 g or more, further preferably 58 g or more. Meanwhile, when the weight of the shaft 3 exceeds 80 g, the entire golf club 1 becomes heavy, so that the golf club is not easily quickly swung. As a result, the head speed is decreased and the flight distance of the ball is lowered. Since the weight is too heavy, the evaluation of the feeling at the time of hitting the ball is also unfavorable.

5

Therefore, the weight of the shaft 3 is preferably 78 g or less, further preferably 75 g or less.

Further, although the length of the shaft 3 itself is not particularly limited in the present invention, it is ordinarily from 105 to 120 cm. If the length of the shaft 3 is too short, a turning radius of the swing becomes small, so that it becomes difficult to obtain a sufficient head speed. As a result, the ball speed cannot be increased, and the flight distance of the ball cannot be extended. Therefore, the length of the shaft 3 is preferably not smaller than 107 cm, and further preferably not smaller than 110 cm. On the other hand, if the length of the shaft 3 is too long, the inertia moment at the grip end becomes large, and a powerless golfer can become easily overwhelmed in terms of power. Therefore, the head speed cannot be increased, and the flight distance of the ball cannot be extended. Thus, the length of the shaft 3 is preferably not larger than 118 cm, and further preferably not larger than 116 cm.

Furthermore, although the position of the center of gravity itself of the shaft 3 is not particularly limited in the present invention, it is ordinarily located within a range of 600 to 750 mm from the tip end 3a (front end) of the shaft 3 in the case of a shaft for example having length of 46 inches. If the center of gravity G of the shaft 3 is located closer than 620 mm from the front end of the shaft 3, it can not be said that the position of the gravity center is sufficiently moved in the gripping direction. Thus, the swingability of the club is not improved, and there is a high possibility that the head speed is not increased at the end. Therefore, the position of the center of gravity of the shaft 3 is preferably, when measured from the front end of the shaft 3, not closer than 615 mm and further preferably not closer than 630 mm. On the other hand, if the position of the center of gravity G of the shaft 3 is farther than 750 mm from the front end of the shaft 3, thickness on the shaft front end side is reduced, and there is a high possibility that the strength such as the bending strength becomes insufficient. Therefore, the position of the center of gravity of the shaft 3 is preferably, when measured from the front end of the shaft 3, not farther than 705 mm and further preferably not farther than 700 mm.

In the present invention, when the distance from the front end of the shaft 3 to the center of gravity G of the shaft is represented as L_G and when the full length of the shaft 3 is represented as L_S , $0.54 \leq L_G/L_S \leq 0.65$ is satisfied.

If L_G/L_S is less than 0.54, the gravity center of the shaft is close to the front end side of the shaft. Thus, in order to get a similar swing balance to a conventional example, the weight of the head is required to be decreased, so that a freedom degree of designing the head is reduced. That is, the inertia moment of the head is reduced, and a gravity center lowering technique cannot be introduced. Therefore, an increase in the flight distance of the ball is not easily achieved. Consequently, L_G/L_S is preferably 0.55 or more, further preferably 0.56 or more.

On the other hand, if L_G/L_S is higher than 0.65, the weight on the hand side of the shaft becomes large and the weight on the front end side of the shaft becomes small when the weight of the shaft is unchanged. As a result, the strength on the front end side of the shaft may become weak. Furthermore, to increase the ratio higher than 0.65 while preventing deterioration of the strength on the front end side of the shaft means to increase the weight on the hand side while maintaining the weight on the front end side of the shaft; and this causes the full weight of the club to be too large and swinging the club becomes difficult. Therefore, L_G/L_S is preferably not higher than 0.64, and further preferably not higher than 0.63.

6

In the present invention, a bending rigidity value EI at a point of 630 mm from the shaft front end to the shaft rear end side is 3.6 kgf·m² or less.

The position of 630 mm from the shaft front end to the shaft rear end side is a part slightly close to the head side from a gripping portion of the grip, and a part where the golfer feels the flex at the time of swing. By suppressing the bending rigidity value EI of this part, the flex of the shaft is utilized so as to improve the head speed. Since the "swingability" is increased by the flex of some extent, the head speed can be further improved.

In a case where the bending rigidity value EI at the point of 630 mm from the shaft front end to the shaft rear end side is less than 2.0 kgf·m², there is a fear that the shaft is flexed too much and the head receives impact late, or the front end of the shaft is flexed too much in the ball hitting direction at the time of impact. Therefore, the hook or the slice is easily produced, and as a result, the flight distance of the ball cannot be extended. Therefore, the bending rigidity value EI is preferably 2.1 kgf·m² or more, further preferably 2.2 kgf·m² or more.

Meanwhile, if the bending rigidity value EI at the point of 630 mm from the shaft front end to the shaft rear end side exceeds 3.6 kgf·m², the flex of the shaft cannot be utilized, so that the head speed cannot be improved. In addition, since the feeling is deteriorated due to hard feel, the bending rigidity value EI is preferably 3.3 kgf·m² or less, further preferably 3.0 kgf·m² or less.

The position of 730 mm from the shaft front end to the shaft rear end side is also a part slightly close to the head side from the gripping portion, and a part where the flex is felt when the club is swung. By suppressing a bending rigidity value EI of this part to be 4.6 kgf·m² or less, the shaft is flexed, so that impact transmitted to hands can be softened. Since the bending rigidity value EI at the position of 730 mm from the shaft front end to the shaft rear end side is close to the grip part, the value largely influences the feel of the golfer.

In a case where the bending rigidity value EI at the point of 730 mm from the shaft front end to the shaft rear end side is less than 2.6 kgf·m², the shaft is flexed too much, and there is a possibility that the head receives the impact late. In addition, since the feeling is not favorable due to excessive softness, the bending rigidity value EI is preferably 2.7 kgf·m² or more, further preferably 2.8 kgf·m² or more.

Meanwhile, if the bending rigidity value EI at the point of 730 mm from the shaft front end to the shaft rear end side exceeds 4.6 kgf·m², the flex of the shaft cannot be utilized, so that the head speed cannot be improved. In addition, since the feeling is deteriorated due to hard feel, the bending rigidity value EI is preferably 4.2 kgf·m² or less, further preferably 3.8 kgf·m² or less.

The shaft 3 can be manufactured by curing a prepreg sheet, and fibers in this prepreg sheet are orientated substantially in one direction. A prepreg whose fibers are orientated substantially in one direction is also referred to as a UD (Uni-Direction) prepreg. It should be noted that, in the present invention, prepregs other than a UD prepreg can also be used, and, for example, a prepreg sheet in which fibers included in the sheet are knitted can also be used.

The prepreg sheet includes a matrix resin formed from a thermosetting resin and the like, and a fiber such as a carbon fiber. As described above, although the shaft 3 can be manufactured through a sheet winding process, the matrix resin is in a semi-cured state in a prepreg form. The shaft 3 is obtained by winding and curing the prepreg. The curing of the prepreg is conducted by applying heat, and steps for manufacturing

the shaft 3 include a heating step. The matrix resin in the prepreg sheet is cured in this heating step.

In the present embodiment, low elasticity prepreg sheets (low elasticity members) containing fibers with a fiber elastic modulus of 20 t/mm² or less are used for a butt side part of the shaft 3. When the fiber elastic modulus exceeds 20 t/mm², the elastic modulus is too high, the bending rigidity value EI of the shaft 3 becomes high, and the feeling at the time of hitting the ball is not favorable. Therefore, the fiber elastic modulus is preferably 18 t/mm² or less.

Meanwhile, a lower limit of the fiber elastic modulus is not particularly limited in the present invention but generally 2 t/mm². In a case where the fiber elastic modulus is less than 2 t/mm², strength as fibers is lowered. Thus, the shaft strength is also lowered. Therefore, the fiber elastic modulus is preferably 3 t/mm² or more.

A fiber orientation angle of at least a part of the fibers with the fiber elastic modulus of 20 t/mm² or less is advantageous for improving the bending strength. Thus, the fiber orientation angle is preferably 0±10 degrees.

The fiber orientation angle of at least a part of the fibers with the fiber elastic modulus of 20 t/mm² or less is advantageous for improving torsional rigidity. Thus, the fiber orientation angle is preferably 45±10 degrees.

In the present embodiment, in a range from a butt end part to a point which is 300 mm away to the shaft tip side (butt side part), the prepreg containing the fibers with the fiber elastic modulus of 20 t/mm² is included by 15 to 50 mass % with respect to the shaft weight. In a case where this content rate is less than 15 mass %, the bending rigidity value EI of the butt part becomes too high. Thus, the impact cannot be eased, and deep vibration remains on hands. Therefore, the above blending rate is preferably 16 mass % or more, further preferably 17 mass % or more. Thereby, the impact transmitted to hands can be sufficiently suppressed. Meanwhile, if this blending rate exceeds 50 mass %, the strength of the shaft is lowered. Thus, there is a fear that the shaft is broken during swing. Therefore, the above blending rate is preferably 48 mass % or less, further preferably 46 mass % or less.

The matrix resin of the prepreg sheet is also not particularly limited in the present invention, and, for example, thermoplastic resins and thermosetting resins such as epoxy resins can be used. From a standpoint of enhancing the strength of the shaft, an epoxy resin is preferably used.

As the prepreg, a commercially available product can be used as appropriate, and the following Table 1-1 and Table 1-2 show examples of prepgs that can be used as the shaft of the golf club of the present invention.

TABLE 1-2-continued

Manufacturer Name	Prepreg Sheet Stock Number	Carbon Fiber Physical Property Value		
		Carbon Fiber Stock Number	Tensile Elastic Modulus* (t/mm ²)	Tensile Strength* (kgf/mm ²)
Mitsubishi Rayon Co., Ltd.	HRX350C-110S	HR40	40	450

*Tensile strength and tensile elastic modulus are values measured in accordance with JIS R7601: 1986 "testing methods for carbon fibers".

FIG. 2 is an expansion plan (sheet block diagram) of the prepreg sheet forming the shaft 3. The shaft 3 includes multiple sheets, and in the embodiment shown in FIG. 2, the shaft 3 includes eleven sheets of a1 to a11. The expansion plan shown in FIG. 2 shows the sheets forming the shaft, sequentially from the inner side of a radial direction of the shaft. In the expansion plan, winding is conducted sequentially from a sheet located on the upper side. Further, in the expansion plan shown in FIG. 2, the right-left direction in the drawing coincides with the axial direction of the shaft, the right side in the drawing is the tip end 3a side of the shaft 3, and the left side in the drawing is the butt end 3b side of the shaft 3.

It should be noted that, in the present specification, a term "layer" and a term "sheet" are used. The "sheet" is a designation for those prior to being wound, and the "layer" is a designation for the sheets after being wound. The "layer" is formed by winding the "sheet." Furthermore, in the present specification, the same reference character is used for a layer and a sheet. For example, a layer formed by winding the sheet a1 is described as a layer a1.

Furthermore, in the present specification, regarding the angle of a fiber with respect to the axial direction of the shaft, an angle Af and an absolute angle θ_a are used. The angle Af is an angle that is associated with a plus or a minus, and the absolute angle θ_a is an absolute value of the angle Af. The absolute angle θ_a is an absolute value of an angle between the axial direction of the shaft and a fiber direction. For example, "the absolute angle θ_a being equal to or smaller than 10°" means "the angle Af being not smaller than -10° but not larger than +10°".

The expansion plan shown in FIG. 2 not only shows a winding sequence of each of the sheets, but also shows a position of each of the sheets in the axial direction of the shaft. For example, the end of the sheet a1 is located at the tip end 3a, and the end of the sheet a8 is located at the butt end 3b.

The shaft 3 includes straight layers, bias layers, and a hoop layer. The expansion plan shown in FIG. 2 describes an orientation angle of a fiber included in the prepreg sheet; and a sheet having a description of "0°" forms a straight layer. A sheet for the straight layer is also referred to as a straight sheet in the present specification. In addition, a sheet for the bias layer is also referred to as a bias sheet in the present specification.

The straight layer is a layer whose fiber orientation is substantially 0° with respect to a longitudinal direction of the shaft (axial direction of the shaft). However, there are cases where the direction of the fiber is not perfectly 0° with respect to the axial direction of the shaft, due to errors at the time of winding. Ordinarily, in the straight layer, the absolute angle θ_a is equal to or smaller than 10°.

In the embodiment shown in FIG. 2, the straight sheets are the sheet a1, the sheet a2, the sheet a7, the sheet a8, the sheet

a9, the sheet a10, the sheet a11, and the sheet a12. The straight layer is highly correlated with flexural rigidity and flexural strength of the shaft.

The bias layer is a layer whose fiber orientation is slanted with respect to the longitudinal direction of the shaft. The bias layer is highly correlated with twist rigidity and twist strength of the shaft. The bias layer is preferably formed from a pair of two sheets whose fiber orientations are slanted in directions opposite to each other. From a standpoint of twist rigidity, the absolute angle θ_a of the bias layer is preferably equal to or larger than 15°, more preferably equal to or larger than 25°, and further preferably equal to or larger than 40°. On the other hand, from the standpoint of twist rigidity and twist strength, the absolute angle θ_a of the bias layer is preferably equal to or smaller than 60°, and more preferably equal to or smaller than 50°.

In the embodiment shown in FIG. 2, the bias sheets are the sheet a3, the sheet a4, the sheet a5 and the sheet b6. In FIG. 2, the angle Af is described for all of the sheets. Plus (+) and minus (-) of the angles Af indicate that fibers of the bias sheets are slanted in directions opposite to each other. It should be noted that, in the embodiment shown in FIG. 2, although the angle Af of the sheet a3 and the sheet a5 are -45° and the angle Af of the sheet a4 and the sheet a6 are +45°, contrary to that, the angle Af of the sheet a3 and the sheet a5 may be +45° and the angle Af of the sheet a4 and the sheet a6 may be -45°.

It should be noted that although not used in the embodiment shown in FIG. 2, the hoop layer in which the orientation angle of the fibers is substantially 90° with respect to the shaft axial direction can be used. There is sometimes a case where the direction of the fiber is not perfectly 90° with respect to the axial direction of the shaft, due to errors at the time of winding. Ordinarily, in the hoop layer, the absolute angle θ_a is not smaller than 80° but not larger than 90°.

The hoop layer contributes to enhancing crush rigidity and crush strength of the shaft. The crush rigidity is rigidity against crushing force toward the inner side of the radial direction of the shaft. The crush strength is strength against crushing force toward the inner side of the radial direction of the shaft. The crush strength is also related to flexural strength. Furthermore, crush deformation may occur associated with flexural deformation. This association is particularly large for a thin lightweight shaft. By improving the crush strength, flexural strength can be improved.

Although not diagrammatically represented, the prepreg sheet before it is being used is sandwiched between cover sheets. Ordinarily, a cover sheet consists of a release paper and a resin film, and the release paper is pasted on one surface of the prepreg sheet, and the resin film is pasted on the other surface. In the following description, the surface on which the release paper is pasted is also referred to as "release paper side surface" and the surface on which the resin film is pasted is also referred to as "film side surface."

The expansion plans in the present specification are diagrams in which the film side surface is on the front side. In other words, in the expansion plans in the present specification, the front side in the drawing is the film side surface, and the reverse side in the drawing is the release paper side surface. In the expansion plan shown in FIG. 2, the fiber direction of the sheet a2 and the fiber direction of the sheet a3 are identical, whereas when being attached as described later, the sheet a3 will be turned over. As a result, the fiber direction of the sheet a2 and the fiber direction of the sheet a3 become directions opposite to each other, and thereby, in a state after the winding, the fiber direction of the sheet a2 and the fiber direction of the sheet a3 will be directions opposite to each

11

other. This point is taken into consideration, and in FIG. 2, the fiber direction of the sheet a2 is denoted as “-45°” and the fiber direction of the sheet a3 is denoted as “+45°.”

In order to wind the above described prepreg sheet, firstly, the resin film is peeled. By peeling the resin film, the film side surface becomes exposed. This exposed surface has tackiness (adhesiveness) originating from the matrix resin. Since the matrix resin of the prepreg at the time of the winding is in a semi-cured state, the matrix resin expresses adhesiveness. Next, a margin part (wind-start margin part) on the exposed surface of the film side is attached to a to-be-wound object. Attaching to the wind-start margin part can be smoothly conducted due to the adhesiveness of the matrix resin. The to-be-wound object is a mandrel, or a wound object obtained by winding another prepreg sheet on a mandrel.

Next, the release paper of the prepreg sheet is peeled. Then, the to-be-wound object is rotated to wind the prepreg sheet on the to-be-wound object. In the manner described above, first, the resin film is peeled; next, the wind-start margin part is attached to the to-be-wound object, and then, the release paper is peeled. With such a procedure, occurrences of wrinkling of the prepreg sheet and inferior winding can be prevented. The release paper has high flexural rigidity when compared to the resin film, and a sheet having such release paper attached thereto is supported by the release paper and is unlikely to wrinkle.

In the embodiment shown in FIG. 2, a merged sheet formed by attaching two or more sheets together is employed. For the embodiment shown in FIG. 2, two merged sheets shown in FIGS. 3 and 4 are employed. FIG. 3 shows a first merged sheet a34 formed by attaching the sheet a3 and the sheet a4 together. In addition, FIG. 4 shows a second merged sheet a56 formed by attaching the sheet a5 and the sheet a6 together.

The procedure for manufacturing the first merged sheet a34 will be described below. First, the bias sheet a4 is turned over, and the turned over bias sheet a4 is attached to the bias sheet a3. At that time, as shown in FIG. 3, a butt end and a tip end of the bias sheet a4 are each attached to the bias sheet a3 so as to be misaligned from a long side of the bias sheet a3.

As a result, the sheet a3 and the sheet a4 of the merged sheet a34 are misaligned from each other by about half a wind in the shaft after the winding.

As shown in FIG. 4, in the second merged sheet a56, as the merged sheet 34, the bias sheet a6 is reversed, and this reversed bias sheet a6 is applied to the bias sheet a5. At that time, as shown in FIG. 4, the sheets are applied to each other in a state that a butt end and a tip end of the bias sheet a6 are respectively displaced from a long side of this bias sheet a5.

As described above, in the present specification, although the sheets and layers are classified by their fiber's orientation angle in the prepreg, the sheets and layers can be further classified by their length in the axial direction of the shaft.

In the present specification, a layer arranged over the whole axial direction of the shaft is referred to as a full length layer, and a sheet arranged over the whole axial direction of the shaft is referred to as a full length sheet. On the other hand, in the present specification, a layer partially arranged in the axial direction of the shaft is referred to as a partial layer, and a sheet partially arranged in the axial direction of the shaft is referred to as a partial sheet.

In the present specification, a straight layer that is a full length layer is referred to as a full length straight layer. In the embodiment shown in FIG. 2, the sheet a7, the sheet a9 and the sheet a10 form the full length straight layers after the winding.

In addition, in the present specification, a straight layer that is a partial layer is referred to as a partial straight layer. In the

12

embodiment shown in FIG. 2, the sheet a1, the sheet a2, the sheet a8, the sheet a11, and the sheet a12 form the partial straight layers after the winding.

In the present specification, a term “butt partial layer” is used. The butt partial layer is one mode of the partial layer, and is a partial layer that is located on the butt end 3b side. Shown in FIG. 2 with a reference character of “A1” is a point located on the most butt side on a side of the butt partial layer in the tip side. Preferably, the point A1 is located closer to the 5 butt side than the center position Sc of the axial direction of the shaft. Shown in FIG. 2 with a reference character of “B1” is a middle point of a side of the butt partial layer in the tip side. Preferably, the point B1 is located closer to the butt side than the center position Sc of the axial direction of the shaft. 10 15 The butt partial layer includes a butt straight layer, a butt hoop layer, and a butt bias layer.

In addition, in the present specification, a term “butt straight layer” is used. The butt straight layer is one mode of the partial straight layer, and is a partial straight layer located 20 on the butt end 3b side. Preferably, the entirety of the butt straight layer is located closer to the butt side than the center position Sc of the axial direction of the shaft. The back end of the butt straight layer may or may not be located at the butt end 3b of the shaft. From a standpoint of bringing the position 25 of the center of gravity of the club close to the butt end 3b, preferably, an arrangement range of the butt straight layer includes a position P1 that is separated from the butt end 3b of the shaft by 100 mm. From a standpoint of bringing the position 30 of the center of gravity of the club close to the butt end 3b, more preferably, the back end of the butt straight layer is located at the butt end 3b of the shaft. In the embodiment shown in FIG. 2, the butt straight layer is the sheet a8.

The shaft 3 is manufactured through a sheet winding process using the prepreg sheet shown in FIG. 2. In the following, 35 a general outline of the steps for manufacturing the shaft 3 will be described.

General Outline of Shaft Manufacturing Steps]

(1) Cutting Step

In a cutting step, the prepreg sheet is cut into predetermined 40 shapes, and each of the sheets shown in FIG. 2 is cut out.

(2) Attaching Step

In an attaching step, multiple sheets are attached together to manufacture the merged sheet a34 and the merged sheet a56 described above. For the attaching, applying of heat or 45 pressing can be used; however, from a standpoint of reducing misalignments between sheets forming a merged sheet in a later described winding step and improving accuracy of the winding, the applying of heat and the pressing are preferably used in combination. Although heating temperature and 50 pressing pressure can be selected as appropriate from a standpoint of enhancing the adhesive strength among the sheets, the heating temperature is ordinarily within a range from 30 to 60° C., and the pressing pressure is ordinarily within a range from 300 to 600 g/cm². Similarly, although heating time and 55 pressing time can also be selected as appropriate from a standpoint of enhancing the adhesive strength among the sheets, the heating time is ordinarily within a range from 20 to 300 seconds, and the pressing time is ordinarily within a range from 20 to 300 seconds.

(3) Winding Step

In the winding step, a mandrel is used. A representative mandrel is made from metal, and a mold releasing agent is applied on a circumferential surface of the mandrel. Additionally, a resin (tacking resin) having adhesiveness is applied 60 over the mold releasing agent. The cut sheets are wound on the mandrel which has the resin applied thereon. As a result of the tacking resin, an end part of the sheet can be attached

13

easily to the mandrel. A sheet obtained by attaching multiple sheets together is wound in a state of a merged sheet.

With this winding step, a wound body can be obtained. The wound body is obtained by winding a prepreg sheet on the outer side of the mandrel. The winding is conducted, for example, by rolling a to-be-wound object on a flat surface.

(4) Tape Wrapping Step

In a tape wrapping step, a tape referred to as a wrapping tape is wound on an outer circumferential surface of the wound body. The wrapping tape is wound on the outer circumferential surface of the wound body while being kept in tension. With the wrapping tape, pressure is applied to the wound body and void in the wound body is reduced.

(5) Curing Step

In a curing step, the wound body which has been wrapped with the tape is heated at a predetermined temperature. As a result of the heating, the matrix resin in the prepreg sheet is cured. In the curing process, the matrix resin temporarily fluidizes, and through this fluidization, air within or between the sheets is discharged. The discharging of air is enhanced by the pressure (fastening force) provided by the wrapping tape. With the curing step, a cured lamination body is obtained.

(6) Mandrel Draw-Out Step and Wrapping Tape Removal Step

After the curing step, a mandrel draw-out step and a wrapping tape removal step are conducted. Although there is no particular limitation in the sequence of the two steps in the present invention, from a standpoint of improving efficiency of the wrapping tape removal, the wrapping tape removal step is preferably conducted after the mandrel draw-out step.

(7) Both-Ends Cutting Step

In a both-ends cutting step, both ends of the cured lamination body obtained through each of the steps of (1) to (6) described above are cut. As a result of the cutting, the end surface of the tip end **3a** and the end surface of the butt end **3b** of the shaft become smooth.

(8) Polishing Step

In a polishing step, the surface of the cured lamination body whose both ends are cut is polished. Helical concavities and convexities remain on the surface of the cured lamination body as traces of the wrapping tape used in step (4) described above. As a result of the polishing, the helical concavities and convexities which are traces of the wrapping tape disappear, and the surface of the cured lamination body becomes smooth.

(9) Painting Step

A prescribed paint is applied on the cured lamination body after the polishing step.

With the above described steps, the shaft **3** can be manufactured. The golf club **1** can be obtained by fixing the tip end **3a** of the manufactured shaft **3** in the shaft hole **5** of the hosel **6** of the golf club head **2**, and fixing the butt end **3b** of the shaft **3** in the grip hole **7** of the grip **4**.

One feature of the present invention is that, in the golf club **1** described above, when the distance from the front end **3a** of the shaft **3** to the center of gravity of the shaft is represented as L_G and when the full length of the shaft is represented as L_S , $0.54 \leq L_G/L_S \leq 0.65$ is satisfied and the center of gravity **G** of the shaft **3** is brought close to the hand side.

Reducing club weight is effective in making the club easy to swing. However, the weight of the head which is one element forming the club is a factor that influences an increase in ball speed. Therefore, in the present invention, an approach of increasing the ball speed without reducing the head weight is adopted. By placing the position of the center of gravity of the shaft on the grip side, the inertia moment of the club is reduced to make the club easy to swing.

14

Means for adjusting the position of the center of gravity of the shaft **3** includes, for example, the following (A) to (H). In the present invention, it is possible to bring the position of the center of gravity of the shaft **3** close to the hand side by employing one or more of these means as appropriate.

- (A) Increasing or decreasing the number of windings of the butt partial layer
  - (B) Increasing or decreasing the thickness of the butt partial layer
  - (C) Increasing or decreasing a length L_1 (described later) of the butt partial layer
  - (D) Increasing or decreasing a length L_2 (described later) of the butt partial layer
  - (E) Increasing or decreasing the number of windings of the tip partial layer
  - (F) Increasing or decreasing the thickness of the tip partial layer
  - (G) Increasing or decreasing a shaft-direction length of the tip partial layer
  - (H) Increasing or decreasing a taper rate of the shaft
- <Weight Ratio of Butt Partial Layer>

From a standpoint of placing the position of the center of gravity of the shaft on the grip side, the weight of the butt partial layer with respect to the shaft weight is preferably not smaller than 5 wt %, and more preferably not smaller than 10 wt %. On the other hand, from a standpoint of reducing a stiff feeling, the weight of the butt partial layer with respect to the shaft weight is preferably not larger than 50 wt %, and more preferably not larger than 45 wt %. In the embodiment shown in FIG. 2, a total weight of the sheet **a4** and the sheet **a8** is the weight of the butt partial layer.

<Weight Ratio of Butt Partial Layer in Specific Butt Range>

Indicated as "P2" in FIG. 1 is a point separated from the butt end **3b** by 250 mm. A range from point **P2** to the butt end **3b** is defined as a "specific butt range." When the weight of the butt partial layer existing in the specific butt range is represented as "Wa," and when the weight of the shaft in the specific butt range is represented as "Wb," from a standpoint of placing the position of the center of gravity of the shaft on the grip side, the ratio (Wa/Wb) is preferably not lower than 0.4, more preferably not lower than 0.42, and further preferably not lower than 0.44. On the other hand, from a standpoint of reducing a stiff feeling, the ratio (Wa/Wb) is preferably not higher than 0.7, more preferably not higher than 0.65, and further preferably not higher than 0.6.

<Fiber Elastic Modulus of Butt Partial Layer>

From a standpoint of ensuring strength of the butt partial layer, the fiber elastic modulus of the butt partial layer is preferably not lower than 5 t/mm², and more preferably not lower than 7 t/mm². When the center of gravity of the club is close to the butt end **3b**, centrifugal force that acts upon the center of gravity of the club easily decreases. In other words, when the center-of-gravity position of the shaft is placed on the grip side, the centrifugal force that acts upon the center of gravity of the club easily decreases. In such a case, it becomes difficult to sense the bending of the shaft, and a stiff feeling is easily generated. From a standpoint of reducing a stiff feeling, the fiber elastic modulus of the butt partial layer is preferably not higher than 20 t/mm², more preferably not higher than 15 t/mm², and further preferably not higher than 10 t/mm².

<Resin Content of Butt Partial Layer>

From a standpoint of placing the center-of-gravity position of the shaft on the grip side and reducing a stiff feeling, the resin content of the butt partial layer is preferably not lower than 20 mass %, and more preferably not lower than 25 mass %. On the other hand, from a standpoint of ensuring strength

15

of the butt partial layer, the resin content of the butt partial layer is preferably not higher than 50 mass %, and more preferably not higher than 45 mass %.

<Weight of Butt Straight Layer>

From a standpoint of placing the position of the center of gravity of the shaft on the grip side, the weight of the butt straight layer is preferably not smaller than 2 g, and more preferably not smaller than 4 g. On the other hand, from a standpoint of reducing a stiff feeling, the weight of the butt straight layer is preferably not larger than 30 g, more preferably not larger than 20 g, and further preferably not larger than 10 g.

<Weight Ratio of Butt Straight Layer>

From a standpoint of placing the position of the center of gravity of the shaft on the grip side, the weight of the butt straight layer with respect to the shaft weight W_s is preferably not smaller than 5 mass %, and more preferably not smaller than 10 mass %. On the other hand, from a standpoint of reducing a stiff feeling, the weight of the butt straight layer with respect to the shaft weight is preferably not larger than 50 mass %, and more preferably not larger than 45 mass %. In the embodiment shown in FIG. 3, the total weight of the sheet a4 and the sheet a5 is the weight of the butt straight layer.

<Fiber Elastic Modulus of Butt Straight Layer>

From a standpoint of ensuring strength of the butt part, the fiber elastic modulus of the butt straight layer is preferably not lower than 5 t/mm², and more preferably not lower than 7 t/mm². On the other hand, from a standpoint of reducing a stiff feeling, the fiber elastic modulus of the butt straight layer is preferably not higher than 20 t/mm², more preferably not higher than 15 t/mm², and further preferably not higher than 10 t/mm².

<Resin Content of Butt Straight Layer>

From a standpoint of placing the position of the center of gravity of the shaft on the grip side, and reducing a stiff feeling, the resin content of the butt straight layer is preferably not lower than 20 mass %, and more preferably not lower than 25 mass %. On the other hand, from a standpoint of ensuring strength of the butt part, the resin content of the butt straight layer is preferably not higher than 50 mass %, and more preferably not higher than 45 mass %.

<Maximum Shaft Direction Length L1 of Butt Partial Layer>

Shown as "L1" in FIG. 2 is the maximum shaft direction length of the butt partial layer. The maximum length L1 is determined in each butt partial sheet. In the embodiment shown in FIG. 2, a length L1 of the sheet a4 is different from a length L1 of the sheet a5.

16

From a standpoint of ensuring weight of the butt partial layer, the length L1 is preferably not smaller than 100 mm, more preferably not smaller than 125 mm, and further preferably not smaller than 150 mm. On the other hand, from a standpoint of placing the position of the center of gravity of the shaft on the grip side, the length L1 is preferably not larger than 700 mm, more preferably not larger than 650 mm, and further preferably not larger than 600 mm.

<Minimum Shaft Direction Length L2 of Butt Partial Layer>

Shown as "L2" in FIG. 2 is the minimum shaft direction length of the butt partial layer. The minimum length L2 is determined in each butt partial sheet. In the embodiment shown in FIG. 2, a length L2 of the sheet a4 is different from a length L2 of the sheet a5.

From a standpoint of ensuring weight of the butt partial layer, the length L2 is preferably not smaller than 50 mm, more preferably not smaller than 75 mm, and further preferably not smaller than 100 mm. On the other hand, from a standpoint of placing the position of the center of gravity of the shaft on the grip side, the length L2 is preferably not larger than 650 mm, more preferably not larger than 600 mm, and further preferably not larger than 550 mm.

EXAMPLES

Next, the golf club of the present invention will be described based on Examples; however, the present invention is not limited only to those Examples.

Golf clubs according to Examples 1 to 26 and Comparative Examples 1 to 6 were manufactured in accordance with a hitherto known method, and their performances and characteristics were evaluated. A substantially identical shaped head was used for all the golf clubs, and the volume of the head was 460 cc, and the material of the head was a titanium alloy.

Shafts for the Examples and Comparative Examples were manufactured based on the expansion plan shown in FIG. 2. The used manufacturing method was similar to that used for the shaft 3 described above, and the shafts were manufactured in accordance with the steps of (1) to (9). For each of the sheets a1 to a12, the number of windings, the thickness of the prepreg, the fiber content of the prepreg, and the tensile elastic modulus of carbon fiber etc., were selected as appropriate. Examples of the prepgs used for the shafts in the Examples and Comparative Examples are shown in Table 2. For adjusting the position of the center of gravity of the shafts, one or more of the above described (A) to (H) were used.

Specifications and evaluations of the golf clubs according to Examples 1 to 5 and Comparative Examples 1 to 2 (L_G/L_S is changed) are shown in Table 3. Specifications and evaluations of the golf clubs according to Examples 2, 6 to 9 and Comparative Examples 3 to 4 (EI value at the point of 630 mm from the tip end of the shaft is changed) are shown in Table 4. Specifications and evaluations of the golf clubs according to Examples 2, 10 to 13 and Comparative Examples 5 to 6 (shaft weight is changed) are shown in Table 5. Specifications and evaluations of the golf clubs according to Examples 2, 14 to

19 (EI value at the point of 730 mm from the tip end of the shaft is changed) are shown in Table 6. Specifications and evaluations of the golf clubs according to Examples 2, 20 to 25 (content rate of the prepreg containing the fibers with the fiber elastic modulus of 20 t/mm² or less in the butt side part is changed) are shown in Table 7. Specifications and evaluations of the golf clubs according to Example 2 and Example 26 (orientation angle of the fibers with the fiber elastic modulus of 20 t/mm² or less in the butt side part is changed) are shown in Table 8.

[Evaluation Method]

<Ball Flight Distance (Yards)>

The average total flight distance when a golfer of the average head speed of 45 m/s or more hit five balls was adopted.

<Feeling>

The feeling of the golfer of the average head speed of 45 m/s when the golfer hit the five balls was evaluated on the following 5 point scale.

5: Excellent

4: Good

3: Fair

2: Poor

1: Very poor

<Strength of Shaft Front End (T Point Strength)>

The strength of the shaft front ends (T point strength) was measured in accordance with a safety goods (SG) mark test method. SG type three-point bending strength is SG type fracture strength set by the Consumer Product Safety Association. FIG. 5 is an illustrative view of a measuring method of the SG type three-point bending strength. As shown in FIG. 5, while the shaft 3 is supported at two support points t1, t2 from the lower side, a load F is applied at a load point t3 from the upper side to the lower side. A position of the load point t3 is a position in a half point between the support point t1 and

the support point t2. This load point t3 is matched with a point to be measured (point T), and measurement is performed.

The point T is a point of 90 mm from the head side end (tip end). In a case where this point T is measured, a measurement span in FIG. 3 is 150 mm. Therefore, the support point t1 is positioned at a point of 15 mm from the tip end. A value of the load F (peak value) when the shaft 3 is broken is the SG type three-point bending strength.

<Strength of Butt Part (C Point Strength)>

The butt strength was measured in accordance with the SG mark test method as well as the shaft front end strength described above. In this case, a point C is a point of 175 mm from the butt end of the shaft. In a case where this point C is measured, a measurement span is 300 mm. Therefore, a support point on the butt end side is positioned at a point of 25 mm from the butt end.

From results shown in Tables 3 to 8, it is found that with the golf clubs according to Examples, while extending the flight distance of the ball, the feel and the shaft front end strength can be improved. Meanwhile, for example with the golf club according to Comparative Example 1, L_G/L_S is less than 0.54. Thus, movement of the shaft gravity center to the gripping side is not sufficient. Although the feel and the shaft front end strength produced favorable results, the flight distance of the ball was not extended. Meanwhile, with the golf club according to Comparative Example 2, L_G/L_S exceeds 0.65, and the shaft gravity center is moved to the gripping side too much. Thus, although the flight distance of the ball was sufficient, the shaft front end strength was lowered. With the golf club according to Comparative Example 6, the shaft weight exceeds 80 g. Although the shaft front end strength was favorable, the feeling was poor, and the flight distance of the ball was not really extended.

Regarding the EI value from the tip end, in Example 9, the EI value at the point of 630 mm from the tip end is large. Thus, the feeling is poor in comparison to Examples 7 to 8. In a case where the EI value at the point of 630 mm from the tip end is an upper limit as in Example 9, a flight distance performance

is slightly lowered in comparison to Examples 7 to 8 but favorable in comparison to Comparative Examples. Meanwhile, in a case where the EI value at the point of 630 mm from the tip end exceeds the upper limit as in Comparative Example 4, the flight distance performance is considerably lowered in comparison to Examples 6 to 9.

[Other Modifications]

It should be understood that the embodiments disclosed herein are merely illustrative and not restrictive in all aspects. The scope of the present invention is defined by the scope of the claims rather than by the meaning described above, and is intended to include meaning equivalent to the scope of the claims and all modifications within the scope.

For example, in the above described embodiment, although a shaft having the expansion plan shown in FIG. 2 is adopted as the shaft of the golf club, the present invention is not limited thereto, and, for example, a shaft having an expansion plan shown in FIG. 6 may also be used. The shaft having the expansion plan shown in FIG. 6 includes twelve sheets of b1 to b12. Similar to FIG. 2, the expansion plan shown in FIG. 6 shows the sheets forming the shaft, sequentially from the inner side of the radial direction of the shaft; and winding is conducted sequentially from a sheet located on the upper side in the expansion plan. Further, in the expansion plan shown in FIG. 6, the right-left direction in the drawing coincides with the axial direction of the shaft, the right side in the drawing is the tip end 3a side of the shaft 3, and the left side in the drawing is the butt end 3b side of the shaft 3.

In a modification shown in FIG. 6, the sheet b1, the sheet b5, the sheet b6, the sheet b7, the sheet b8, the sheet b10, the sheet b11, and the sheet b12 are sheets forming the straight layers; the sheet b2 and the sheet b3 are sheets forming the bias layers; and the sheet b4 and the sheet b9 are sheets forming the hoop layers. As the sheets b1 to b12, for example, the following prepgs shown in Table 1 can be used.

Sheet b1; TR350C-125S

Sheets b2, b3; HRX350C-075S

Sheet b4; 805S-3

Sheets b5, b6; E1026A-09N

Sheets b7, b8; TR350C-100S

Sheet b9; 805S-3

Sheet b10; MR350C-100S

Sheets b11, b12; TR350C-100S

In the modification shown in FIG. 6, the major difference from that shown in FIG. 2 is arrangement of the sheet b4, which forms the partial hoop layer, between the sheets b5 and b6, which form the partial straight layers, and the sheets b2 and b3, which form the bias layers.

Also in the modification shown in FIG. 6, a merged sheet formed by attaching two or more sheets together is employed. In the modification shown in FIG. 6, two merged sheets shown in FIGS. 7 and 8 are employed. FIG. 7 shows a first merged sheet b234 formed by attaching the sheet b2, the sheet b3, and the sheet b4 together. In addition, FIG. 8 shows a second merged sheet b910 formed by attaching the sheet b9 and the sheet b10 together.

The procedure for manufacturing the first merged sheet b234 will be described below. A pre-merged sheet b34 is manufactured by attaching two sheets (bias sheet b3 and hoop sheet b4) together. When manufacturing the pre-merged sheet b34, the bias sheet b3 is turned over and attached to the hoop sheet b4. In the pre-merged sheet b34, the upper end of the sheet b4 matches the upper end of the sheet b3. Next, the pre-merged sheet b34 and the bias sheet b2 are attached together. The pre-merged sheet b34 and the bias sheet b2 are attached together in a state where they are misaligned from each other by half a wind.

In the merged sheet b234, the sheet b2 and the sheet b3 are misaligned from each other by half a wind. Thus, in the shaft after the winding, the circumferential direction position of the sheet b2 and the circumferential direction position of the sheet b3 are different. The angular difference here is preferably 180° (±15°).

As a result of using the merged sheet b234, the bias layer b2 and the bias layer b3 are misaligned from each other in the circumferential direction. With this misalignment, the positions of the ends of the bias layers are spread in the circumferential direction. As a result, it is possible to improve uniformity of the shaft in the circumferential direction. Further, in the merged sheet b234 in the present modification, the entirety of the hoop sheet b4 is sandwiched between the bias sheet b2 and the bias sheet b3. With this, it is possible to prevent inferior winding of the hoop sheet b4 in the winding step. By using the merged sheet b234, it is possible to improve accuracy of the winding. Here, inferior winding means disarray of fibers, generation of wrinkles, and deviation of fiber angle, etc.

Further, as shown in FIG. 8, in the second merged sheet b910, the upper end of the sheet b9 matches the upper end of the sheet b10. In addition, in the sheet b910, the entirety of the sheet b9 is pasted on the sheet b10. As a result, inferior winding of the sheet b9 is prevented in the winding step.

Also in the present modification, it is possible to adjust and bring the position of the center of gravity of the shaft close to the hand side by employing one or more of the previously described means of (A) to (H).

5 shaft hole

6 hosel

7 grip hole

G center of gravity of shaft

L_G distance from the tip end of the shaft to the center of gravity of the shaft

L_S shaft full length

What is claimed is:

1. A golf club shaft having:

a front tip end and a rear butt end, wherein the rear butt end is formed from a low elasticity material including fibers with a fiber elastic modulus of 20 t/mm² or less, a shaft weight in the range 56 grams to 80 grams, and a bending rigidity value EI at a point 630 mm from the shaft front end to the shaft rear end of 3.6 kgf·m² or less and a bending rigidity value EI at a point 730 mm from the shaft front end to the shaft rear end side is in the range 2.7 kgf·m² to 4.6 kgf·m²,

wherein if the distance from the shaft front end to the shaft gravity center point is L_G and the full length of the shaft is L_S , then $0.54 \leq L_G/L_S \leq 0.65$ is satisfied and

wherein the shaft comprises a tubular body formed from multiple fiber reinforced resin layers of full axial length and at least one butt partial layer of partial axial length extending from the rear butt end, P2 is a point separated from the butt end by 250 millimeters, a range from point P2 to the butt end is defined as a specific butt range, Wa is the

weight of the butt partial layer in the specific butt range, and W_b is the weight of the shaft in the specific butt range, and

the relationship $0.4 \leq W_a/W_b \leq 0.7$ is satisfied.

2. The golf club shaft according to claim 1, wherein a fiber orientation angle of at least a part of the fibers in the low elasticity material is 0 ± 10 degrees.

3. The golf club shaft according to claim 1, wherein a fiber orientation angle of at least a part of the fibers in the low elasticity material is 45 ± 10 degrees.

4. The golf club shaft according to claim 1, wherein the low elasticity material includes 15 to 50 mass % of prepreg containing fibers with a fiber elastic modulus of 20 t/mm^2 or less.

5. The golf club shaft according to claim 2, wherein the low elasticity material includes 15 to 50 mass % of prepreg containing fibers with a fiber elastic modulus of 20 t/mm^2 or less.

6. The golf club shaft according to claim 3, wherein the low elasticity material includes 15 to 50 mass % of prepreg containing fibers with a fiber elastic modulus of 20 t/mm^2 or less.

7. A golf club shaft having:

a front tip end and a rear butt end, wherein the rear butt end is formed from a low elasticity prepreg material containing fibers with a fiber elastic modulus in the range 2 t/mm^2 to 20 t/mm^2 ,

a shaft weight of 56 g or more, and

a bending rigidity value EI at a point 630 mm from the shaft front end to the shaft rear end of 3.6 kgf m^2 or less, wherein if the distance from the shaft front end to the shaft gravity center point is L_G and the full length of the shaft is L_S , then $0.54 \leq L_G/L_S \leq 0.65$ is satisfied, and

wherein

the shaft comprises a tubular body formed from multiple fiber reinforced resin layers of full axial length and at least one butt partial layer of partial axial length extending from the rear butt end, $P2$ is a point separated from the butt end by 250 millimeters, a range from point $P2$ to the butt end is defined as a specific butt range, W_a is the weight of the butt partial layer in the specific butt range, and W_b is the weight of the shaft in the specific butt range, and

the relationship $0.4 \leq W_a/W_b \leq 0.7$ is satisfied.

8. The golf club shaft according to claim 7, wherein a fiber orientation angle of at least a part of the fibers in the low elasticity material is 0 ± 10 degrees.

9. The golf club shaft according to claim 7, wherein a fiber orientation angle of at least a part of the fibers in the low elasticity material is 45 ± 10 degrees.

10. The golf club shaft according to claim 7, wherein the low elasticity material includes 15 to 50 mass % of said low elasticity prepreg containing fibers.

11. The golf club shaft according to claim 8, wherein the low elasticity material includes 15 to 50 mass % of said low elasticity prepreg containing fibers.

12. The golf club shaft according to claim 9, wherein the low elasticity material includes 15 to 50 mass % of said low elasticity prepreg containing fibers.

13. A golf club shaft having:
a front tip end and a rear butt end,
a shaft weight of 56 g or more, and
a bending rigidity value EI at a point 630 mm from the shaft front end to the shaft rear end of 3.6 kgf m^2 or less,
wherein if the distance from the shaft front end to the shaft gravity center point is L_G and the full length of the shaft is L_S , then $0.54 \leq L_G/L_S \leq 0.65$ is satisfied, and

wherein the shaft comprises a tubular body formed from multiple fiber reinforced resin layers of full axial length and at least one butt partial layer of partial axial length extending from the rear butt end, $P2$ is a point separated from the butt end by 250 millimeters, a range from point $P2$ to the butt end is defined as a specific butt range, W_a is the weight of the butt partial layer in the specific butt range, and W_b is the weight of the shaft in the specific butt range, and the relationship $0.4 \leq W_a/W_b \leq 0.7$ is satisfied.

14. The golf club shaft according to claim 13, wherein the rear butt end is formed from a low elasticity material including fibers with a fiber elastic modulus of 20 t/mm^2 or less.

15. The golf club shaft according to claim 14, wherein a fiber orientation angle of at least a part of the fibers in the low elasticity material is 0 ± 10 degrees.

16. The golf club shaft according to claim 14, wherein a fiber orientation angle of at least a part of the fibers in the low elasticity material is 45 ± 10 degrees.

17. The golf club shaft according to claim 14, wherein the low elasticity material includes 15 to 50 mass % of prepreg containing fibers with a fiber elastic modulus of 20 t/mm^2 or less.

18. The golf club shaft according to claim 15, wherein the low elasticity material includes 15 to 50 mass % of prepreg containing fibers with a fiber elastic modulus of 20 t/mm^2 or less.

19. The golf club shaft according to claim 16, wherein the low elasticity material includes 15 to 50 mass % of prepreg containing fibers with a fiber elastic modulus of 20 t/mm^2 or less.
